tion of Delaware

Filed Sept. 6, 1961, Ser. No. 136,352

12 Claims. (Cl. 317—22)

This invention relates to repeating circuit interrupters and, more particularly, to the class circuit interrupters commonly known as "Reclosers."

A "Recloser" may be characterized as a circuit protective device having fault-sensing means connected to the system being protected and which is responsive to overload currents to initiate a switch-opening operation, switch reclosing means operable after each opening operation, normally inactive time delay means, and operation counting and lock-out means which is operable to initiate time delayed switch opening after a predetermined number of opening operations.

It is common practice to utilize repeating circuit interrupters of this type in conjunction with other protective devices such as fuses. For example, a distribution system may be provided with a repeating circuit interrupter or recloser connected in series with the main line and located adjacent to the source power and fuses disposed in feeder lines radiating from the main line. Because the majority of faults in such systems are temporary in nature and will clear in a relatively short time, it is common to arrange the switch opening means to execute a series of rapid opening operations so that the period in which the system remains energized is shorter than the time necessary for the fuse element to melt. In addition, the circuit breaker contacts must remain open for a sufficient period of time to allow the fuses to cool. If the fault does not clear during this initial series of rapid operations, the time-delay means is actuated by the operation counting means so that there follows a second series of operations in which the recloser's contacts remain closed for a period of sufficient length to allow the fuse elements to melt. If the fault still has not cleared after a number of such time delayed operations, it is considered permanent and the operation counting means prevents the actuation of the reclosing means so that the device is locked open. In addition, it is desirable for the opening and reclosing times of such reclosers to be sufficiently flexible so that they may be readily coordinated with a plurality of relatively slowly operable circuit breakers.

It is an object of the invention to provide a repeating circuit interrupter having electroresponsive switch-opening means with selectively interchangeable time-delay means and means for successively actuating said selectively interchangeable time-delay means during successive switch-opening operations.

A further object of the invention is to provide a repeating circuit interrupter having reclosing means and a selectively interchangeable time delay means operable to initiate reclosing after each opening operation.

These and other objects and advantages of the instant invention will become more apparent from the detailed description thereof taken with the accompanying drawing in which:

FIG. 1 is a perspective view of a repeating circuit interrupter incorporating the instant invention;

FIG. 2 is a schematic illustration of the electrical control for the recloser shown in FIG. 1;

FIG. 3 shows the overcurrent responsive portion of the control illustrated in FIG. 2; and

FIG. 4 shows the control cabinet of the recloser illustrated in FIG. 1.

In general terms the invention comprises a repeating

2

circuit interrupter having operating means for selectively performing switch opening and reclosing operations. Control means are also provided and include sensing means operable upon the occurrence of an abnormal circuit condition to initiate the operating means in the execution of a switch opening and a switch reclosing operation. The control means also includes time delay circuit means for delaying at least one of said operations and having disconnect plug means for electrically and mechanically coupling it to the control means. In this manner the time delay means may be selectively removed from circuitry with the operating means and replaced by time delay means having different time delay characteristics.

Referring now to the drawings in greater detail, FIG. 1 shows a repeating circuit interrupter or recloser 6 housed in a metallic container and mounted on a metal framework 7. A separate control housing 8 is mounted on the frame 7 and is electrically connected to the recloser 6 by a cable 9. Terminals 20 and 21 connect the recloser 6 to the polyphase system being protected.

The repeating circuit interrupter 6 is shown in FIG. 2 to generally include main interrupting switches 10, overcurrent responsive means 12, switch-opening means 14, switch-closing means 16, and operation counting and lock-out means 17. The overcurrent responsive means 12 is operable to actuate the switch-opening means 14 upon the occurrence of an overload in the system being protected so that the interrupting switches 10 will each be moved to their open positions. Upon this event, reclosing means 16 is made operable to return the interrupting switches 10 to their closed position. The operation-counting and lock-out means 17 which includes stepping relay 18 and step switch 134, is operable to initiate time-delayed open and/or reclosing operations if the fault has not cleared after an initial series of rapid operations and to prevent reclosure of the main switches 10 if the fault does not clear after a second series of such delayed operations. For a more complete description of a circuit breaker operating mechanism usable with the illustrated control mechanism, reference is made to co-pending application Serial No. 56,259 filed September 15, 1960.

The overcurrent responsive means 12 is shown coupled to phase A of a polyphase system by means of a current transformer 22 and a full wave rectifier 24. As will be seen hereinafter, the overcurrent responsive means 12 is similarly connected by means of current transformers and full wave rectifiers each of the other phases B and C. The overcurrent responsive means 12 includes an overcurrent sensing portion 26, a timing portion 27 and an output portion 28. The overcurrent responsive means 12 will be discussed in greater detail below, it being sufficient at this point to state that the overcurrent sensing portion 26 is operable when the rectified current at the output of rectifier 24 exceeds a minimum value to provide a signal to the timing portion 27. Upon the receipt of this signal, the timing portion 27 initiates a timing operation, and after a predetermined interval provides a signal to the output portion 28 which initiates a switch opening operation by closing contacts 43.

The switch opening means 14 is shown in FIG. 2 to include an electromagnetic tripper 30 having a plunger 32 and a coil 36. The plunger 32 is mechanically coupled to a latch crank 33 which is normally urged in a clockwise direction about pivot point 34 by a reset spring 35 to hold the main switches 10 in closed position against the influence of opening spring 69. The trip coil 36 is connected by conductor 37 to the negative power supply terminal 40 and by a conductor 42 to contacts 43. Conductor 44 connects the other side of contacts 43 through a step switch 134 to the positive

power supply terminal 46. The purpose of the step switch 134 will be discussed more fully below, it being sufficient at this point to state that under normal conditions of operation, it is initially on contact *a*. Contacts 43, which are mechanically connected to the output portion 28 of the overcurrent responsive means 12, are normally open so that coil 36 remains de-energized under normal conditions.

Upon the occurrence of a fault in one of the phases, A, B or C, output portion 28 will be made operative to closed contacts 43, thereby energizing coil 36. Upon this event, the latch crank 33 will be rotated in a counter-clockwise direction to release the main switches 10 for movement toward their open position under the influence of opening spring 69. When the main switches 10 open, contacts 43 are returned to their open position to de-energize trip coil 36 so that latch crank 33 may be returned to its initial position by reset spring 35. The trip portion 14 is thereby reset in a position to relatch the main switches 10 when they are returned to their closed positions.

Before continuing the discussion of the mechanical portion of the recloser's control, the operation of the stepping relay 18 will be mentioned briefly. This device accomplishes operation counting and lock-out of the recloser in conjunction with step switch 134. In addition, the stepping relay 18 is also operable to change the time delay for the opening and reclosing operations by operating the tap switches 146 and 147 in the timing portion 27 of overcurrent responsive means 12 and the time delay relay bank 121, respectively. Prior to the first opening operation, the step switch 134 and tap switches 146 and 147 are each disposed on position *a*. The stepping relay 18 is connected by conductors 38 and 45 in parallel with the opening coil 36. When contacts 43 are closed by output portion 28 upon the occurrence of a fault, therefore, the circuit between the negative and positive terminals 40 and 46 will be completed through stepping relay 18 which then operates stepping switch 134 and tap switches 146 and 147 to their positions *b*. Thus, it can be seen that each time the device executes an opening operation, the relay 18 will advance each of the switches 134, 146 and 147 one position.

The reclosing assembly 16 includes a closing coil 120, a time delay relay bank 121 and normally open contacts 122 which are mechanically connected to the main switches 10. Conductors 124 and 125 connect the closing coil 120 to the negative supply terminal 40 through the contacts 122. Conductor 130 connects the other side of closing coil 120 to the time delay relay bank 121 which in turn is connected to the positive power supply 46 through step switch 134.

When the main switches 10 are in their closed position, contacts 122 are open so that the closing coil 120 and the time delay relay bank 121 will be de-energized. When the main switches 10 reach their fully opened positions, the contacts 122 will be closed to complete the circuit through the time delay relay bank 121. As will be discussed more fully below, the time delay relay in bank 121 that is connected to tap *b* will close after a time delay to complete the circuit through closing coil 120. This attracts the magnetic plunger 93 upwardly to reclose the main switches 10 and extending the opening spring 69 to store energy for the succeeding opening operation, and opening contacts 122 to de-energize the closing coil 120 and the time delay relay bank 121.

FIG. 3 shows the details of the overcurrent sensing portion 26, the timing portion 27 and the output portion 28 of the overload responsive means 12. Circuit 12 is coupled with the phases A, B and C by current transformers 22, 22' and 22'' respectively and corresponding full wave rectifiers 24, 24' and 24'' whose secondaries are connected in parallel so that the current flowing to circuit 12 is proportional to the highest peak current flowing to any said rectifiers. In order to limit the cur-

rent flowing to the circuit 12 resistors 200, 200' and 200'' are connected across each of the secondaries of current transformers 22, 22' and 22'' respectively.

The timing portion 27 of circuit 12 includes four identical timing circuits which are each connected to one of the taps *a*, *b*, *c* and *d* of tap switch 147 and correspondingly labeled 201*a*, 201*b*, 201*c* and 201*d*. Because each of the timing circuits is identical, except of course for the size of its components which determine its time delay, only timing circuit 201*a* will be discussed in detail, for the sake of brevity. This circuit is shown to include a timing capacitor 202 connected in series with a timing resistor 204 and a diode 206. A second timing resistor 207 is connected in parallel with this series combination. As more fully discussed in co-pending application Serial No. 800,567, filed March 19, 1859, and assigned to the assignee of the instant invention, the impedance values of capacitor 202 and resistors 204 and 207 determine the charging time for any given fault current in phases A, B or C. Under normal operating conditions, tap switch 147 will be initially connected to tap *a* so that timing circuit 201*a* will govern the first opening operation. In addition, capacitor 205 will be charged to the peak voltage across the resistor 200, 200' or 200'' having the largest IR drop.

In operation, the current flowing in the collector of the charging transistor 208 which is a function of the voltage across capacitor 205 will split between the parallel paths defined by the timing resistor 207 and the series combination of timing resistor 204 and timing capacitor 202. When there is no fault in any of the phases, capacitor 202 is prevented from charging because it is shunted by leakage resistor 209 through diode 210 and conductor 211. The current flowing to the overcurrent sensing portion 26 through conductor 212 is also proportional to the highest peak current in any of the phases A, B or C and causes a transistor 213 collector current to flow through resistors 214 and 216 thereby raising the potential of the junction point 217 between them to a value which is also proportional to said peak current. A transistor 218 emitter current, which is controlled by the potential of junction point 217, flows through a resistor 220 and thereby also raises the potential of junction point 221 to a value proportional to said highest peak current. The base of a signal comparing transistor 222 is connected to junction point 221 while its emitter is connected to junction point 223 which is held at a fixed potential by a Zener diode 224 and a resistor 226. Thus, by a proper selection of components, when the highest peak current of any of the phases A, B or C equals or exceeds the desired minimum actuating current of the device, the base voltage of transistor 222 can be made to exceed its emitter voltage so that collector current will begin flowing therefrom to the base of an output transistor 227. Upon the latter event, the base potential of transistor 227 will fall below its emitter potential whereupon current will begin flowing to the leakage resistor 209. This, in turn, raises the potential at junction point 228, between the collector of transistor 227 and conductor 211, above that across timing capacitor 202. As a result, timing capacitor 202 is prevented from discharging through leakage resistor 209 and therefore, begins charging. In this manner, the timing operation is initiated. Diode 210 performs the function of preventing reverse current flow from junction point 228 to the charging capacitor 202.

As timing capacitor 202 charges up, the voltage at junction point 230, between diode 206 and the base of a coupling transistor 231 in the output portion 28, will begin raising so that the emitter current flowing in transistor 231 and transistor 232, which are proportional to the voltage at junction point 230 will similarly rise. The potential of junction point 233, resulting from the transistor 232 emitter current will, therefore, also follow the potential of junction point 230. The base of a transistor 234, which is connected to junction point 233, will, there-

fore, always be at a potential proportional to the potential at junction point 230 while its emitter will be held at a constant potential by a Zener diode 235 and a resistor 236 connected across the power supply terminals 40 and 46. After timing capacitor 202 has charged for a predetermined time, which is the time delay for the first operation of the device, the potential of junction point 233 will exceed the potential on the emitter of transistor 234 and said transistor will conduct, passing emitter current to the relay 237 which, in turn, closes contacts 43 to open the main switches 10 in the manner described hereinabove. In addition, stepping relay 18 will also be energized so that tap switch 147 will be moved to contact *b* thereby connecting time delay circuit 201b and disconnecting time delay circuit 201a. Should the fault reappear the time delay of the second opening operation will be dictated by the components of time delay circuit 201b.

The time delay relay bank 121 is shown in FIG. 2 to include three distinct time delay relays symbolized by coils 121b, 121c and 121d, although it will be appreciated by those skilled in the art that any type of time delay relay, such as the thermal type, may be employed. Each coil 121b, 121c and 121d is connected between the corresponding taps *b*, *c* and *d* on switch 147 and the negative supply terminal 40 and each coil is operative upon being energized and after a time delay, to close the appropriate contacts 121b', 121c' or 121d', to complete the circuit between the closing coil 120 and taps *b*, *c* and *d* of switch 147.

Assume, for the sake of illustration, that it is desired to have the recloser execute two rapid and two time delayed opening operations, a single rapid and two time delayed reclosing operations followed by lock-out. As a result, relatively short time delay circuits will be connected by disconnect plugs 240a and 240b to contacts *a* and *b* of the timing portion 27 while long time delay circuits will be connected by disconnect plugs 240c and 240d to tap *c* and *d* respectively. In addition, disconnect plugs 242a, 242b, 242c and 242d connect each of the time delay circuits to the input transistor 208 while disconnect plugs 244a, 244b, 244c and 244d connect each of the time delay circuits to the overcurrent sensing portion 26. Similarly, a relatively fast relay will be connected by disconnect plugs 246b, 248b and 250b to tap *b* of switch 147, while correspondingly numbered disconnect plugs will connect relatively slow time delay relays to taps *c* and *d*. Taps *e* and *f* of switches 134, 146 and 147 are dummy contacts for the purpose of lock-out as will be explained in greater detail below.

The first opening operation will be rapid because contact *a* of switch 147 is connected to a short time delay circuit and because stepping relay 18 has not as yet operated. As a result, the output portion 28 will close contact 43 a relatively short time after the fault is sensed by overcurrent sensing portion 26. This energizes trip coil 36 which opens the main switches 10 and also the stepping relay 18 which moves the stepping switch 134 and tap switches 146 and 147 to their *b* positions. Movement of tap switch 147 to contact *b* completes the energizing circuit through short time delay relay 121b, which, after a short time delay, closes contacts 121b' to energize the closing coil 120 through switches 134 and 147, conductors 44, 130, 124, 125 and contacts 122 which are closed when the main switches 10 are open.

Should the fault persist, the output portion 28 will again be energized after a short time delay to close contact 43. This will again energize trip coil 46 and stepping relay 18 so that switches 134, 146 and 147 will each be moved to their taps *c* whereupon time delay coil 121c will be energized to close contacts 121c' after a time delay and thereby energize closing coil 120 and initiate a second reclosing operation. Similarly, should the fault persist after the second reclosing operation, trip coil 36 will be energized after a relatively long time delay

to again open the main switches 10. In a like manner, after the third opening operation, stepping relay 18 will move with each of the switches 134, 146 and 147 to their positions *d*, whereupon closing coil 120 will be energized through contacts 121d' after a time delay. If the fault continues after the third reclosing operation, switch 43 will be reclosed after a time delay dictated by the time delay circuit 201d. This will again energize the trip coil 36 and stepping relay 18 which will then move each of the tap and stepping switches to the dummy contacts *e*.

It can be seen that because contacts *e* of switches 134 and 147 are dummies, closing coil 120 is now open circuited even though contacts 122 are closed when the main switches 10 are open. In this manner, the recloser is locked in open position after a predetermined number of opening and closing operations.

It can be seen in FIG. 2 that diodes 148c and 148d will isolate each of the taps *C* and *D* respectively of switch 134 from the one immediately preceding it, e.g., diode 148c isolates tap *c* from tap *b*, etc. This allows the number of operations before lock-out to be adjusted. In the preceding discussion, when lead 149 was connected to tap *d*, there were four opening operations prior to lock-out. Assume, however, that only two opening operations before lock-out are desired. Here lead 149 will be connected to tap *b*. After the first opening operation switch 134 will be on tap *b* and reclosure will occur in the above described manner. After the second opening operation, however, switch 134 will be on tap *c* and hence isolated by diode 148c from lead 149 and, as a result, from the closing coil 120. Thus, the reclosure is locked out after two operations. Similarly, by connecting lead 149 to tap *c* there will be three operations to lock-out and by opening switch 149' there will be one operation to lock-out.

Resetting of the recloser after it has locked out electrically is accomplished by means of a manual reset button 165 and stepping switch 167 which is mechanically coupled to stepping relay 18. It will be remembered that after lockout each of the step and tap switches 134, 146 and 147 as well as 167 will each be connected to taps *e*. When reset button 165 is depressed stepping relay coil 18 will be energized from the positive terminal 46 to the negative terminal 40 through a path defined by tap *e* of step switch 167, conductor 175, switch 171, and conductors 172, 38, 45 and 37. Upon being energized stepping relay 18 will move each of the tap and step switches to their positions *f*. An energizing circuit to stepping relay 18 is then completed through the tap *f* on step switch 134, conductors 174, 175, switch 171, and conductors 172, 38, 45 and 37. The stepping relay 18 then moves each of the switches to their taps *a* whereupon they are in position for a switch closing operation. Diode 177 connected between stepping relay 18 and trip coil 36 prevents energization of the latter during the resetting operation just described.

After the step and tap switches have been cycled to their positions *a* by reset button 165 the main switches 10 are reclosed by closing switch 169 which completes an energizing circuit to closing coil 120 around the time delay relay bank 121.

It will be recalled that the recloser will cycle itself to lockout only if the fault current persists after a predetermined number of opening and closing operations. In order to reset the device should the fault clear after a lesser number of opening and reclosing operations, the time delay reset assembly 185 is provided. This includes a time delay relay coil 186 connected through diodes 186B, 186C and 186D to taps *b*, *c* and *d* of step switch 147 and in parallel with the corresponding time delay relay windings 121b, 121c and 121d. Time delay relay winding 186 is operable when energized to close normally open contacts 187 which shunts reset button 165. Assume, for example, that after a single opening

and reclosing operation the fault clears so that switch 43 remains open and step switch 18, trip coil 36 and reclosing coil 120 remain de-energized. As a result, each of the step and tap switches will be in their positions *b*. This will energize time delay coil 185 through diode 186. After a time delay, which is longer than the combined time delays of relays 121*b*, 121*c* and 121*d* and each of the opening time delay circuits 201*a*, 201*b*, 201*c* and 201*d*, seen in FIG. 3, contacts 187 will close to energize step switch 18 in the same manner as when reset button 165 has been closed. Stepping relay 18 will then cycle each of the step and tap switches to their positions *a* whereupon time delay relay 185 will be de-energized and contacts 187 will open.

In order to provide energy to the fault current sensing portion 12 whenever the main contacts 10 are closed regardless of the position of the control circuit of FIG. 2, contacts 190 are shown coupled to the main switches 10 and closed when said main switches are closed. Should a fault occur in one of the phases when the control circuit is in lock-out condition, switch 43 will be closed to open the main switches 10 thereby providing protection to the system A, B and C.

Referring now to FIG. 4, the metallic control housing 8 is shown with its front access door 252 pivoted to its open position. Certain of the components of the control circuit are shown to be mounted on a panel 254 which is mounted by hinges 255 to one of the side walls of the housing 8 so that it may be swung outwardly relative to said housing to expose the remainder of the control system components.

Each of the time delay circuits 201*a*, 201*b*, 201*c* and 201*d* are shown to be disposed in a metallic tube 256. For purposes of illustration tube 256*a*, containing the time delay circuit 201*a*, is shown with parts broken away and removed to expose socket 257*a* for receiving the disconnect plugs 240*a*, 242*a* and 244*a* which connect the time delay circuit 201*a* to the overload responsive circuit 12. Tube 256*a* is shown to include an insulating base 260 to which the disconnect plugs 240*a*, 242*a* and 244*a* are affixed. Also affixed to the base 260 and extending normally thereto is a nonconducting circuit board 262 which carries a row of terminals 263 along each of its sides. The components of the circuit 201*a*, capacitor 202, resistors 204 and 207 and diode 206, are soldered at their opposite ends to pairs of terminals 263. Circuitry (not shown) at the rear of the circuit board 262 connects these elements in the manner shown in FIG. 3 and to the disconnect plugs 240*a*, 242*a* and 244*a*.

By mounting the time delay circuits 201*a*, 201*b*, 201*c* and 201*d* in this manner each may be rapidly removed from the overload responsive circuit 12 and a time delay circuit having a different time delay value substituted therefor. As a result, the time delay of the recloser 6 may be rapidly and easily modified by changing one or more of the time delay tubes 256*a*, 256*b*, 256*c* or 256*d*. In addition, it will be appreciated that this may be accomplished merely by opening cover 252 of the housing 8 and without removing the recloser 6 from service. This is contrasted with prior art devices wherein modification of the time delay could only be accomplished by removal of the recloser 6 from service and then removing its metallic housing.

In a similar manner each of the time delay closing relays in bank 121 are disposed in corresponding tubes 265*b*, 265*c* and 265*d* respectively. The tube 265*b* is shown with parts broken away and removed to expose the socket 264*b* for receiving its disconnect plugs 246*c*, 248*c* and 250*c* which connect them to the time delay relay bank 121. The illustrated relay 221*b* is of the thermal type although any well known type may be employed. In general, the device includes a heater coil 121*b* mounted on a mica plate 266 and a pair of oppositely oriented bimetallic elements 267 and 268 which carry the contacts 221*b*' at their upper ends and whose lower ends are

5 mounted on a nonconducting base 270 such as glass. The lower ends of the elements 267 and 268 are further separated by porcelain blocks 272. A Bakelite cap 274 is affixed to the base 270 and supports the disconnect plugs 246*b*, 248*b* and 250*b* which are connected to the coil 121*b* and the contacts 121*b*' through the elements 267 and 268 in the manner shown in FIG. 3. Element 268 is not materially affected by the heater coil 121*b* and provides ambient temperature compensation.

10 Thus, each of the time delay closing relays may also be rapidly removed from the circuit and a relay having a different time delay value substituted therefor. Thus the time delay of each closing operation may also be rapidly modified while the recloser 6 remains in service.

15 While only a single embodiment of the invention has been shown and described and while the invention has been discussed with reference to one type of circuit interrupter, it is not intended that the invention be limited thereby but only by the scope of the appended claims.

I claim:

1. A repeating circuit interrupter including main switch means in circuit with an electrical system, operating means for selectively performing switch opening and switch reclosing operations, control means for said operating means including sensing means operable upon the occurrence of an abnormal condition in said system to actuate said operating means in the execution of a switch opening operation and a reclosing operation, time delay circuit means for delaying at least one of said operations, disconnect plug means electrically and mechanically coupling said time delay means to said control means so that said time delay means may be selectively removed from circuitry with said operating means and replaced by time delay circuit means having different time delay characteristics.

2. A repeating circuit interrupter including main switch means in circuit with an electrical system, operating means for selectively performing switch opening and switch reclosing operations, control means for said operating means including mounting means, overload sensing means operable upon the occurrence of an overload in said system to actuate operating means in the execution of a series of switch opening and reclosing operations, a plurality of time delay circuit means for delaying certain of said operations and each being secured to individual base means, a plurality of socket means in said mounting means, disconnect plug means secured to each of said base means and engageable with one of said socket means for supporting each of said time delay means on said mounting means and electrically connecting the same to said control means, means operable after each opening operation of said main switch means to couple one of said plurality of time delay means to said operating means so that the time delay of each succeeding delayed operation may be controlled, said disconnect plug means allowing said time delay means to be selectively removed from said circuit interrupter and replaced by time delay circuit means having different time delay characteristics.

3. A repeating circuit interrupter for protecting an electrical system and including main switch means in circuit with an electrical system, electroresponsive switch opening means and electroresponsive switch reclosing means; control means for said circuit interrupter, a mounting panel for supporting said control means, said control means including a first and second time delay circuit means each of which is disposed in an individual envelope, a plurality of socket means in said mounting panel, disconnect plug means associated with each of said envelopes and engageable with said socket means for securing said time delay means to said panel and electrically coupling the same to said control means, and overload sensing means coupled to said system and operable upon the occurrence of an overload to actuate said switch opening means through said first time delay circuit means, said switch closing means being energized through said

second time delay means after each switch opening operation, said disconnect plug and socket means allowing the opening and reclosing time delays of said opening and reclosing means to be selectively changed by substituting time delay circuit means having different characteristics.

4. A repeating circuit interrupter for protecting an electrical system and including main switch means in circuit with an electrical system, electroresponsive switch opening means and electroresponsive switch reclosing means, said circuit interrupter being disposed in a metallic housing; control means for said circuit interrupter disposed exteriorly of said housing, a mounting panel for supporting said control means, cable means connecting said control means to said switch opening and reclosing means, said control means including a first and second series of time delay circuit means, each of said time delay circuit means being disposed in an individual envelope, a plurality of socket means in said mounting panel, disconnect plug means associated with each of said envelopes and engageable with one of said socket means for securing said time delay means to said panel and electrically coupling the same to said control means, sequencing means actuatable upon the occurrence of each switch opening operation for sequentially coupling said first series of time delay circuit means to said switch opening means and said second series of time delay means to said switch closing means, and overload sensing means coupled to said system and operable upon the occurrence of an overload to actuate said switch opening means through a different one of said first series of time delay circuit means, said switch closing means being energized through a different one of said second series of time delay means after each switch opening operation, said disconnect plug and socket means allowing the opening and reclosing time delays of said opening and reclosing means to be selectively changed by substituting time delay circuit means having different characteristics.

5. A repeating circuit interrupter including main switch means in circuit with an electrical system, switch opening means, control means including overload sensing means operable upon the occurrence of an overload in said system to actuate said switch opening means, a plurality of time delay circuit means for delaying the openings of said switch means, means operable after each opening operation of said main switch means to actuate a different one of said plurality of time delay means so that the time delay of each succeeding opening operation may be controlled, disconnect plug means electrically and mechanically coupling said time delay means to said control means so that each of said time delay circuit means may be selectively removed from operative association with said switch opening means and replaced by time delay circuit means having different time delay characteristics.

6. A repeating circuit interrupter including main switch means in circuit with an electrical system, switch opening and reclosing means; control means for said circuit interrupter including mounting means, overload sensing means operable upon the occurrence of an overload in said system to actuate said switch opening means, a plurality of time delay circuit means for delaying the openings of said switch means and each being secured to individual base means, a plurality of socket means in said mounting means, disconnect plug means secured to each of said base means and engageable with one of said socket means for supporting said time delay means on said mounting means and electrically connecting the same to said control means, means operable after each opening operation of said main switch means to actuate a different one of said plurality of time delay means so that the time delay of each succeeding opening operation may be controlled, said disconnect plug means allowing said time delay means to be selectively removed from said circuit interrupter and replaced by time delay circuit means having different time delay characteristics.

7. A repeating circuit interrupter for protecting an electrical system and including main switch means in circuit with said system, electroresponsive switch opening means and switch reclosing means, said circuit interrupter being disposed in a metallic housing; control means for said circuit interrupter disposed exteriorly of said housing, a mounting panel for supporting said control means, cable means connecting said control means to said switch opening and reclosing means, said control means including a series of time delay circuit means, each of said time delay circuit means being disposed in an individual envelope, a plurality of socket means in said mounting panel, disconnect plug means associated with each of said envelopes and engageable with said socket means for securing said time delay means to said panel and electrically coupling the same to said control means, sequencing means actuatable upon the occurrence of each switch opening operation for sequentially coupling said time delay circuit means to said switch opening means and overload sensing means coupled to said system and operable upon the occurrence of an overload to actuate said switch opening means through a different one of said first series of time delay circuit means, said disconnect plug and socket means allowing the opening and reclosing time delays of said opening and reclosing means to be selectively changed by substituting time delay circuit means having different characteristics.

8. A repeating circuit interrupter including main switch means in circuit with an electrical system, switch opening means and electroresponsive switch reclosing means; control means for said circuit interrupter including overload sensing means operable upon the occurrence of an overload in said system to actuate said switch opening means, means operable after each opening operation of said main switch means to complete an energizing circuit to said switch reclosing means, time delay circuit means for delaying the actuation of said reclosing means, disconnect plug means electrically and mechanically coupling said time delay means to said control means so that said time delay means may be selectively removed from operative association with said switch opening means and replaced by time delay circuit means having different time delay values.

9. A repeating circuit interrupter including main switch means in circuit with an electrical system, switch opening and reclosing means; control means for said circuit interrupter including mounting means, overload sensing means operable upon the occurrence of an overload in said system to actuate said switch opening means, means for actuating said reclosing means after each switch opening operation, time delay circuit means for delaying the closing of said switch means and secured to a base, a plurality of socket means in said mounting means, and disconnect plug means secured to said base and engageable with said socket means for supporting said time delay means on said mounting means and electrically connecting the same to said control means, said disconnect plug means allowing said time delay means to be selectively removed from said circuit interrupter and replaced by time delay circuit means having different time delay values.

10. A repeating circuit interrupter for protecting an electrical system and including main switch means in circuit with said system, switch opening means and switch reclosing means, said circuit interrupter being disposed in a metallic housing; control means for said circuit interrupter disposed exteriorly of said housing and including means responsive to an overload in said system to actuate said switch opening means, a mounting panel for supporting said control means, cable means connecting said control means to said switch opening and reclosing means, said control means including a series of time delay circuit means each of which are disposed in an individual envelope, a plurality of socket means in said mounting panel, disconnect plug means associated with each of said envelopes and engageable with said socket means for

11

securing said time delay means to said panel and electrically coupling the same to said control means, sequencing means actuatable upon the occurrence of each switch opening operation for sequentially coupling said series of time delay means to said switch closing means, said switch closing means being energized through a different one of said series of time delay means after each switch opening operation, said disconnect plug and socket means allowing the opening and reclosing time delays of said opening and reclosing means to be selectively changed by substituting time delay circuit means having different characteristics.

10

12

11. The repeating circuit interrupter set forth in claim 1 wherein said time delay circuit means is operative to delay one of said switch opening operations.

12. The repeating circuit interrupter set forth in claim 1 wherein said time delay circuit means is operative to delay one of said switch reclosing operations.
